UNITED STATES PATENT OFFICE.

HENRY HUSSONG AND JOSEPH HUSSONG, OF CAMDEN, NEW JERSEY.

DYEING-MACHINE.

SPECIFICATION forming part of Letters Patent No. 394,694, dated December 18, 1888.

Application filed May 3, 1888. Serial No. 272,656. (No model.)

To all whom it may concern:

Be it known that we, HENRY HUSSONG and JOSEPH HUSSONG, citizens of the United States, residing in the city and county of Camden, State of New Jersey, have invented a new and useful Improvement in Dyeing-Machines, which improvement is fully set forth in the following specification and accompanying drawings.

10 Our invention relates to improvements in dyeing-machines, and has for its leading object to provide a machine in which a large amount of material may be dyed rapidly and perfectly.

15 A further object is to provide a machine which will possess superiority over other machines of the same character in points of simplicity, durability, effectiveness, and cheapness.

20 The invention consists, first, in the peculiar construction of the carriage which holds the yarn; second, in the mechanism employed for imparting combined oscillating and sliding motions to said carriage; and, third, in the 25 combination and arrangement of parts, as herein set forth and claimed.

Figure 1 represents a top plan view of a dyeing-machine constructed in accordance with and embodying our invention. Fig. 2 30 represents a side elevation, partly broken away to more clearly show certain features of the invention.

Similar letters of reference indicate corresponding parts in the two figures.

35 Referring to the drawings, A represents the vat, of any desired size and preferably of a square or oblong shape.

B represents the frame or cage which carries the material, and this frame comprises 40 the standards b and b', the connecting-bars b² b³, through which the rods b⁴ pass, and the bars b⁵, connected with the end rods, b⁶, and which serve to hold the material on the rods, and also allow the material to be removed and re-

45 placed with ease, said bars b⁵ being removable for this purpose. The standards b b' are provided near their lower ends with slots b⁶, and in these slots the ends of the lower connecting-bar, b³, are secured, and the said connecting-bar is made vertically adjustable in said 50 slots by means of openings b⁷ and a pin, b⁸,

which passes through the opening b⁷ and the connecting-bar. The purpose of making the connecting-bar adjustable in the frame is to accommodate different lengths of skeins of 55 yarn or other material. To the outer face of the standards b b' are secured ears, arms, or lugs C, through which pass transverse rods C', the purpose of which will presently appear. 60

D represents plates attached to the sides of the vat and projecting outward. Said plates have studs D', which pass through openings in arms E, forming a pivot for said arms. The arms E have weights e at their lower ends, 65 the purpose of which will appear, and at their upper ends are formed with bearings e' for the ends of the rods C', to which the frame is connected, and the ends of said rods are held in their bearings and allowed to be removed 70 therefrom by means of the covers or caps e², which are retained in place by means of the pins or pegs e³.

F designates an arm connected loosely at its inner end with one of the rods C', cut out 75 on its under side near the outer end at f' to engage the upper end of the arm G. The arm G has an opening in its lower end, through which passes the operating rock-shaft H, working in bearings in the outer ends of brackets 80 J, secured to the vat, and has its upper end bifurcated or forked to receive a stud or pin which is engaged by the recessed end of the arm F, and the rock-arm G is secured to the rock-shaft H by a screw, g. 85

The rock-shaft H is operated by steam-power or by hand, as desired.

The operation is as follows: The vat is filled with dyeing-liquid and the cage or frame placed therein with the material thereon, the 90 same being passed around the rods on the lower and upper connecting-bars. The rods on the frame are secured on their bearings and the arm F caused to engage the rock-arm, the rock-shaft transmitting motion to the frame 95 or cage and causing it to move slowly back and forth in the dyeing-liquid and effect the thorough dyeing of the material. The weights on the ends of the arms E serve to render the action of the said arms uniform and even, preventing a jerky motion thereof during the 100 movement of the cage. When the material

has been dyed, the frame is lifted from the vat and the weighted arms assume vertical position, in order to permit the easy replacement of the frame in the bearings.

5 It is evident that we provide a machine of very simple and inexpensive construction, by means of which material may be dyed with rapidity and efficiency. We would also state that a number of dyeing-machines may be 10 operated by the same rock-shaft.

The frame or cage, as is evident, is entirely covered or submerged in the dyeing-liquid, and as it moves back and forth in the liquid 15 a slight up-and-down motion is given the frame, which motion causes the dyeing-liquid to pass under the material when it rests upon the rods, and thus dyes the same at every point.

Having thus described our invention, what 20 we claim as new, and desire to secure by Letters Patent, is—

1. In a dyeing-machine, the combination of the vat, a carriage in said vat and having at both of its ends cross-bars secured thereto, 25 and weighted levers pivotally secured to the sides of the vat and having their unweighted ends resting on said cross-bars, substantially as described.

2. A dyeing-machine having a vat, a frame 30 consisting of uprights, a top and a lower bar connected to said uprights, and rods passing horizontally through said bars, lugs on said uprights, transverse rods passing through said lugs, arms pivotally secured to the sides of the 35 vat and connected to the ends of the transverse rods, an arm loosely connected to one of the transverse rods, and a rocking shaft with an attached arm connected to said mentioned arm, said parts being combined substantially 40 as described.

3. In a dyeing-machine, the combination of the vat, the frame or cage arranged therein, said frame having rods passing through lugs secured to its upper portion, and the pivoted arms having bearings in their upper ends for 45 said rods, substantially as described.

4. In a dyeing-machine, a vat with carriage therein, an arm, F, pivotally secured to said carriage at one end thereof, a bracket secured to one end of the vat, and an arm pivotally 50 secured to the bracket and engaged by the said arm F, said parts being combined substantially as described.

5. In a dyeing-machine, a vat with carriage therein having cross-bars at each end, 55 weighted levers pivotally attached to the vat and bearing against the cross-bars, an arm pivotally secured to the end of the vat and having a bifurcated front end with pin, and an arm pivotally attached to one end of the 60 carriage and having its outer end engaging with the pin on the bifurcated end of said arm, said parts being combined substantially as and for the purpose set forth.

6. A vat, a cage having the transverse rods 65 C', the arms E, pivot to the sides of the vat and connected with the ends of the transverse rods, the arm F, loosely mounted on one of the rods C', and having the cut-away portion f, the rock-shaft H, and the arm G, connected to 70 said rock-shaft and engaging the arm F, said parts being combined substantially as described.

HENRY HUSSONG.
JOSEPH HUSSONG.
